(No Model.)

B. SCARLES.

LOOM SHUTTLE.

No. 359,546.

Patented Mar. 15, 1887.

UNITED STATES PATENT OFFICE.

BENJAMIN SCARLES, OF CLINTON, MASSACHUSETTS, ASSIGNOR TO THE
CLINTON WIRE CLOTH COMPANY, OF SAME PLACE.

LOOM-SHUTTLE.

SPECIFICATION forming part of Letters Patent No. 359,546, dated March 15, 1887.

Application filed July 23, 1886. Serial No. 209,303. (No model.)

To all whom it may concern:

Be it known that I, BENJAMIN SCARLES, of Clinton, county of Worcester, and State of Massachusetts, have invented an Improvement 5 in Loom-Shuttles, of which the following description, in connection with the accompanying drawings, is a specification, like letters on the drawings representing like parts.

10 Prior to my invention shuttles employed in looms for weaving wire-cloth have been provided with cop-chambers to receive cops of wire, the said chambers occupying, however, but a small portion of the central part of the 15 shuttle, a great portion of the main body of the shuttle being taken to receive the devices instrumental in drawing the wire from the center of the cop at one end and its delivery to the delivery-rolls.

20 In the shuttle herein described, as in my application Serial No. 208,599, filed July 21, 1886, the chamber is of sufficient length to receive a long cop containing a large amount of wire, which is drawn from the interior of the 25 cop through an opening in a wall or plate located at one end of the cop-chamber, and thereafter the wire is passed about a sheave, the supporting pivot or axle of which is placed at an angle to the bottom of the shuttle, the wire, 30 after passing partially about the said diagonally-placed sheave, being carried to a sheave at the rear wall of the shuttle, and from thence across the cop to the front wall of the shuttle, the wire then being led out from the shuttle 35 between usual delivery-rolls, such location of the sheaves about which the wire is led enabling me to utilize a greater portion of the body of the shuttle as a cop-chamber. The larger the cop-chamber, the greater quantity 40 of wire which can be formed into a cop and placed therein.

The shuttle herein to be described is an improvement upon that described in my said application, in that I have provided means for automatically varying the tension on the wire as 45 the latter is drawn from the interior of the cop.

The shuttle herein to be described also contains within its cop-chamber a cop-holding plate, which is preferably corrugated or 50 notched to aid in preventing the cop from slip-

ping longitudinally in the said chamber, the plate also aiding in keeping the outer coils of the wire in shape. More power is required to draw the wire from the interior or center of the cop when the wire is first started from the 55 center of the cop, where the coils are small, than after the wire has been partially unwound; or, in other words, the power required to draw the wire from the cop decreases as the coils increase in diameter or approach the outer layer 60 or coil of wire forming the cop. This variation in the delivery of the wire from the shuttle to the fabric must be counteracted by the tension mechanism, in order to gain uniformity of product and maintain uniform selvages. 65

In the invention herein to be described the hole through which the wire is led as it passes from the cop to the diagonally-placed sheave is made to present a convexed or bulged surface at that side of the wall nearest the delivery end of the cop, so that as the cop is unwound the wire is gradually bent more and more about the said convexed or bulged surface, thus gradually increasing the friction upon the wire, which produces an increased 70 tension, the increase of tension being gradual as the cop is unwound, to thus compensate for the decreasing resistance of the coils of larger diameter as they leave the cop.

By the employment of the convexed or bulged friction-surface to constitute a tension device, it is possible to make the hole through the partition in line with the longitudinal center of the cop of smaller diameter than heretofore, as when a conical hole is employed, 75 and by reason of the convexed or bulged surface the wire is straightened before entering the said hole, and hence it may be delivered from the said hole to the sheave more freely and without liability of being caught or clogged 80 by gradually reducing coils in the wire, as is now the case when the hole through which the wire is led is conical.

Figure 1, in top view partially broken out, shows a shuttle embodying my invention. 90 Fig. 2 is a vertical longitudinal section of Fig. 1 in the line *x*, the cop being omitted, the said figures showing, however, the wire as passing straight through the central opening of the tension device. Fig. 3 is a cross-section 95

of Fig. 1 in the dotted line x' , looking toward the left; Fig. 4, a section of Fig. 1 in the dotted line x'' , chiefly to show the face of the tension device. Fig. 5 is a detail to be referred to, 5 it showing the cover-holding spring at one side of the cop-chamber. Fig. 6 is a detail showing the wire bent about the tension device, the tension being nearly at its maximum; and Fig. 7 shows the spring g' separately.

10 The shuttle-body A, preferably of metal, has a long chamber extending some distance in each way from its center in the direction of its length, so as to receive a long cop, C, wound so as to be delivered from its center at one 15 end, as common in shuttles for use in wire-weaving looms. The shuttle-body contains a division-wall, B, which serves the function of a tension device. This wall has a central opening, 2, which for a part of its length is nearly 20 cylindrical; but at its inner face the wall about the said opening is convexed or bulged, as at 25 3, to present a friction-surface, over and against which the wire 4 will be gradually bent and drawn as layer after layer thereof is pulled out from the interior of the cop C.

In Fig. 2 the wire is represented as passing through the central part of the hole 2 without touching the convexed or bulged friction-surface 3, the wire being at such time drawn from 30 the coils of smaller diameter, or the coils at and near the longitudinal center of the cop; but as the wire is gradually unwound from the interior of the cop and the coils increase in diameter, the resistance to unwinding decreases, and to compensate for this decreasing 35 resistance the wire coming from the coil of increasing diameter is gradually bent about the convexed or bulged surface 3, the wire touching a greater and greater extent of the 40 said surface, thus increasing the tension or drag upon it and insuring uniform delivery.

The shuttle-body receives within it the sheave c , mounted upon a pivot or axle, c' , held by the sheave-block c' , (shown as attached 45 to the shuttle by the screw 5,) the said pivot c' being placed diagonally with relation to the bottom of the shuttle, as in my said application.

From the sheave c' the wire is led through 50 the hole 6 and about the sheave d on the stud d' , erected on the cover D for the shuttle-body, the wire 4 being led from the sheave d between the delivery-rolls e , e' , the sheaves c and d and the delivery-rolls being substantially 55 as in my said application, and operating in like manner to insure uniform bending of the wire in both directions of movement of the shuttle.

The cover D is herein shown as pivoted at 60 one end, as at D' , on a plate, D'' , in turn pivoted at D'' , the flanged edge 8 of the cover being bent at right angles, so as to enter the shuttle, as at the left of Fig. 3 and as shown in Fig. 5. This flanged edge 8 is slotted, as 65 at 10, to engage a pin or projection, 12, in the shuttle-body, to thus keep the cover D from

being accidentally opened, the said cover also having a lug, 13, which is engaged by the stud 14 (see Fig. 1) of a spring-latch or cover-locking device, 15, which acts to keep the 70 cover from longitudinal movement, thus keeping the hooked or slotted part 10 of the cover in engagement with the stud or pin 12.

The cover may be moved longitudinally to be opened whenever the locking device 15 is 75 pulled outward to remove the projection 14 from the lug 13.

Any other equivalent or well-known form of device to lock the cover may be employed 80 instead of those shown.

The interior of the shuttle-body is provided with a notched or toothed plate, f , upon which the cop C rests, the teeth of the said plate (shown in Figs. 2 and 5) being preferably turned in opposite directions, to thus engage 85 and hold the wire-cop against longitudinal movement in the shuttle.

The shuttle-body within the cop-chamber has a spring-presser, g^2 , serrated at its surface and supported upon spring-arms g , a 90 curved spring, g' , (shown separately in Fig. 7 and in section, Fig. 3,) inserted between the inner side of the presser-plate and the inner wall of the shuttle, normally acting to move the presser-plate against the cop. This spring 95 g' is so shaped and the arms g are so attached to the shuttle-body and the presser-plate that the latter is kept pressed against the cop and is enabled to adapt itself to even a tapering cop, for the plate held as described may move 100 unequally at its opposite ends toward or from the cop. The bulged tension-surface herein shown is claimed in a shuttle, and I have described a similar surface in another application, Serial No. 220,584, filed December 3, 105 1886, for improvement in machine for the manufacture of wire-netting.

I claim—

1. The shuttle-body provided with a tension device composed of a block or wall having a passage through it and having a convexed or bulged surface, over which are drawn the coils of material coming from a cop being unwound from its center outward, the material coming in more extended contact with the 115 said convexed or bulged surface as the cop is being unwound, thus producing an increasing friction to equalize the delivery of the material from the shuttle, substantially as described.

2. The shuttle-body, the presser-plate, and arms g , to support it, combined with the spring g' , inserted between the said presser-plate and shuttle-body, substantially as described.

In testimony whereof I have signed my name 125 to this specification in the presence of two subscribing witnesses.

BENJAMIN SCARLES.
